UNITED STATES PATENT OFFICE.

WILLIAM C. CROSS, OF BOSTON, MASSACHUSETTS.

NECKTIE.

SPECIFICATION forming part of Letters Patent No. 288,561, dated November 13, 1883.

Application filed October 6, 1883. (No model.)

To all whom it may concern:

Be it known that I, WILLIAM C. CROSS, of Boston, Suffolk county, Massachusetts, have invented certain new and useful Improvements 5 in Neckties, of which the following is a specification.

My invention has relation to means for securing the neck tie or scarf in place on the neck of the wearer, and it has particular reference to that kind of neck tie or scarf which is sustained and held by means of a loop which catches upon the collar-button. Loops of elastic cord have long been in use for this purpose; but they are objectionable in many respects. When 10 fresh, their retractile force is such that they draw up the necktie too forcibly and frequently cause the collar, if it be separate from the shirt, to rise. Moreover, the elasticity of the loops 15 soon becomes impaired, so that they are incapable of holding the tie or scarf properly up in place.

It is my object to furnish a durable, readily-applied, and effective substitute for the elastic loop, one which, like the latter, can be extended, so as to conveniently pass around the collar-button, and which then can be contracted so as to draw up and hold securely the neck tie or scarf in its proper place. This 25 result I attain by means of instrumentalities 30 which can best be explained and understood by reference to the accompanying drawings, in which—

Figure 1 is a view from the rear side of a neck tie or scarf embodying my invention in 35 its preferred form. Fig. 2 is a plan of the metal cord-holder detached.

The tie or scarf is of any ordinary or suitable construction. The loop for attaching it to the collar-button is applied, as usual, to the 40 rear face of the necktie-shield A, and consists of a cord, *a*, held at one of its ends, as *x*, (either movably or immovably,) to the necktie, with its other end, *y*, passing through what may be termed an "eye," *b*. The cord can, by pulling 45 with some force on it from above or below the eye, be drawn up or down therethrough, so as to enlarge or contract the loop to the desired extent. At the same time the eye clasps the cord so tightly that it will remain at any 50 point therein to which it may be drawn. By the term "eye" I intend a clasp of metal or

some hard material, through which or between whose faces the cord can pass, the frictional contact between the two being such that the cord cannot be moved therein unless pulled 55 with considerable force.

I have before remarked that the other end, *x*, of the loop is held either movably or immovably to the scarf or necktie. I prefer that it shall, like the end *y*, be held thereto movably; and to this end I connect it to the necktie by an eye, *c*, in precisely the same way that end *y* is connected thereto by its eye *b*. The advantage of this is that both ends of the cord can be pulled down at once when the loop 60 is shortened in the act of drawing up the necktie in place, and in like manner, when the necktie is pulled down by the hand, in order to disengage it from the neck, both ends of the cord travel up an equal distance in their respective 65 eyes; and I thus avoid pulling the cord lengthwise over the shank of the button, as would be the case were one of its ends only drawn upon. In Fig. 1 the loop is represented by full lines in its contracted position and by 70 dotted lines in its extended position. The collar-button is indicated by dotted lines at *s*.

The eyes are carried by a plate, *B*, which is secured in any proper manner to the tie. I prefer to form them from one piece of sheet 75 metal, which is also provided with prongs *d*, for attaching the device to the tie. The device thus constructed and termed by me the "holder" is represented plainly in Fig. 2.

Any suitable cord or the like can be used, 80 whether elastic or inelastic. I much prefer, however, that it should be inelastic, and it is this kind of cord that I in practice use.

I remark also that while I have described in illustration of my invention a holder which 85 is well adapted for the purpose I have in view, the construction of the same can be varied considerably without departure from my invention, the characteristic of which, as will be seen from the foregoing specification, resides 90 in the combination, with a scarf or necktie, of a collar-button loop adapted to be lengthened or shortened at will, and a holding device which 95 retains said loop in any position to which it may be adjusted.

What I claim as new and of my invention 100 is—

1. The combination, with a neck tie or scarf, of a collar-button loop adapted to be lengthened or shortened at will by a sliding movement of the cord of which it is composed, and
5 a holder which maintains said loop in its adjusted position, as and for the purposes hereinbefore set forth.
2. The sheet-metal holder consisting of plate B, eyes *b c*, and prong *d*, in combination with

the neck tie or scarf and the cord *a*, substantially as hereinbefore set forth.

In testimony whereof I have hereunto set my hand this 4th day of October, 1883.

WILLIAM C. CROSS.
